UNITED STATES PATENT OFFICE.

EDGAR R. CREAMER, OF CONNERSVILLE, INDIANA, ASSIGNOR TO THE GEORGE R. CARTER COMPANY, OF CONNERSVILLE, INDIANA, A CORPORATION OF INDIANA.

MOLDING.

Application filed March 18, 1925. Serial No. 16,331.

To all whom it may concern:

Be it known that I, EDGAR R. CREAMER, a citizen of the United States, residing at Connersville, Indiana, in the county of Fayette and State of Indiana, have invented certain new and useful Improvements in Molding, of which the following is a specification.

This invention relates to an improvement 10 in a molding for upholstering used in automobiles and furniture and is especially adapted to window molding. It is moreover arranged to assume all kinds of shapes suitable to conform to the curves and lines of 15 various styles of windows now being used in automobile construction.

A main feature in the device is in the combination of a resilient core or holding 20 element such as rubber or similar rigid material having a limited amount of flexibility with a covering of thin flexible material such as cloth, the cloth being arranged to cover the fastening devices for the core. The 25 arrangement is such that the cloth is very easily applied to the top of the holder and the free edge of the cloth is so arranged as to be readily forced between the core and the article to be held, with provision for 30 engaging the ends of the cloth at the point where the ends engage the sides of the core.

Referring to the figures of the drawing, Fig. 1 is an elevation showing the cloth or cover partly assembled, Fig. 2 is a vertical sectional view through the glass and the 35 holder, and Fig. 3 is a sectional view of a modification.

Referring to Fig. 1, the support for the device is marked 1 and represents the casing of a frame of an automobile. This casing 40 is often formed with a ledge 2 for supporting the glass or similar part. The core itself is indicated by 3 and the securing devices for the holder are marked 4. As clearly shown in Figs. 1 and 2, the holder is 45 preferably formed of triangular shape and has two grooves formed near the corners, the grooves being marked 5. The holder fits snugly against the glass with the two grooves 5 near the exposed surface of the 50 holder. The fastenings 4 are applied to the rubber to hold same securely to the casing or support as indicated in Fig. 1, and these fastenings are preferably arranged about an inch or an inch and a fraction 55 apart. As indicated in Fig. 1, the core is

capable of assuming shapes to follow the curved line of the casing that holds the vertical part of the glass, as well as the horizontal part thereof. The cloth or cover is marked 6 and one edge of this cloth or cover is formed with a bead 7, these beads being of a material of such character as to give stiffness to the edges and to form a curved end capable of being readily inserted within the groove 5 formed in the sides of the 65 core 3.

As indicated in Figs. 1 and 2, one end of the cloth is clamped by the bottom of the core and is securely held by the fastening device 4. The cloth is then rolled around 70 the holder until the edge having the bead or re-enforcing member 7 is brought adjacent to the surface of the glass, then with a putty knife or some similar instrument the edge of the cloth is pushed between the core 75 and the glass until the bead 7 slips into the groove 5. Plastic material such as cement may be used to give an additional holding effect of the cloth upon the holder, but one of the main advantages of this arrangement 80 is that both the holder and the cover or cloth are capable of being applied to a curved surface in such a manner that there will be eliminated any danger of wrinkling of the cover due to the peculiar configuration of 85 the article to which the holder is applied.

In Fig. 3 the core is marked 3 and the cover is marked 6; the core with the cover secured to the bottom portion of the core is fastened to the support by the tacks 4 90 and the cover is then wrapped around the top portion of the core thereby concealing those devices and the free end of the cover is readily forced beneath the bottom edge 95 of the core until the enlarged edge passes into the groove 5, thereby securing the cover around the core in substantially the same manner as in Figs. 1 and 2.

Having described the invention, I claim 100 as follows:

1. In a molding of the character described, the combination, with a structure to which said molding is to be applied, a resilient core, a flexible cover for said core, means for securing said core to said structure with one edge of the cover clamped between said core and structure, said securing means being such as to leave at least one edge of said core free to flex away from said structure, and interlocking means formed on the 110

5 said free edge of said core and the other edge of said cover whereby by flexing the free edge of said core away from said structure said last mentioned edge of said cover 5 may be inserted therebetween and caused to interlock with said core to hold the cover in position.

2. In a molding of the character described, 10 the combination, with a structure to which 10 said molding is to be applied, of a pliable cover, a bead arranged along one edge of said cover, a resilient core, fastening devices for securing said core to said structure but leaving at least one of its edges free to flex 15 away from said structure, the under side of said core being formed with a groove adjacent to but removed from the free edge thereof, that edge of said cover opposite the bead being clamped to said support by said 20 core with the intermediate portion of the cover adapted to overlie the outer side of said core, the flexibility of said core permitting the grooved edge thereof to be flexed away from said structure to permit the insertion in said groove of the bead of said 25 cover.

3. In an article of the character described, the combination, with a structure to which 30 said molding is to be applied, of a pliable cover, a resilient core of less pliability than said cover but having sufficient pliability to enable it to be bent into the necessary positions it must assume, a bead carried by one of the edges of said cover, fastening devices 35 for attaching said core to said structure in a manner to leave at least one edge of said core free to flex away from said structure, the under side of said core having a groove 40 adjacent to but removed from the free edge of said core, that edge of said cover opposite said bead being clamped between said structure and said bead, the resilient character of the material of said core permitting the free edge thereof to flex away from said structure to allow the insertion of said bead in said groove and thereafter to spring back to position against said structure to stretch the intermediate portion of the cover over said bead and clamp the same to position.

In testimony whereof, I have hereunto set 50 my hand this 12th day of March, 1925.

EDGAR R. CREAMER.
